UNITED STATES PATENT OFFICE.

MICHAEL M. GARDNER, OF CRANSTON, RHODE ISLAND.

CIGAR-BUNCHING MACHINE.

SPECIFICATION forming part of Letters Patent No. 699,674, dated May 13, 1902.

Application filed August 5, 1901. Serial No. 70,868. (No model.)

To all whom it may concern:

Be it known that I, MICHAEL M. GARDNER, a citizen of the United States of America, and a resident of Edgewood, in the town of Cranston, in the county of Providence and State of Rhode Island, have invented certain new and useful Improvements in Cigar-Bunching Machines, of which the following is a specification.

- 10 My invention relates to certain novel improvements in "cigar-bunching machines," so called, and of the type in which the entire stripped leaf of tobacco is used for the "fillers" of the cigar-bunches. A cigar-bunching
15 machine of this class is clearly illustrated and described in United States Patent No. 523,903, granted to Henry K. Gardner November 6, 1894. In that machine the suitably-prepared leaves of tobacco are superposed in a traveling trough, so as to form a comparatively thick layer or continuous strip or ribbon, which is fed to a yielding ironing device adapted to flatten out or iron the strip of tobacco-leaves, so that the latter will lie straight
20 and even and at the same time being substantially uniform in thickness. The thus-treated strip is intermittently fed into a contiguous magazine a suitable distance, corresponding with the length of cigar to be produced therefrom, and severed. The severed portion or section is then advanced in said magazine-chamber, together with other previously-severed sections then lying side by side therein, by means of a yieldingly-mounted
25 30 35 40 45 50 55 60 65 70 75 80 85 90 95 100
plunger, so as to press the front portion of the horizontal column of fillers or sections into a suitably-shaped open chamber or charging-pocket formed in the charging-head, followed by severing or shearing off the charge of fillers in the head from the said column of sections lying in the magazine. The charge of fillers is then discharged from the head into the usual bight formed in the bunch-rolling apron, the action of the latter being to properly roll the binder around the charge of fillers, thus completing the bunch. In the said cigar-bunching machine patented to H. K. Gardner an adjustable feeding device is employed and also a yieldingly-mounted plunger adapted to press the filler-sections into the magazine. It also shows a means for controlling or regulating the length of the

sections, but no mechanism for automatically stopping the feeding device in case the magazine becomes surcharged with the filler-sections.

My present invention, as before stated, relates to cigar-bunching machines, but more especially to improved devices for feeding the tobacco and controlling the length of the severed filler-sections, which latter are later transferred into a magazine and adapted to be converted into bunches.

It also relates to new and improved means for automatically rendering the feeding device temporarily inoperative in case the quantity of fillers in the magazine exceeds a predetermined amount.

In carrying out my invention I employ a continuously-reciprocating rack and gear, which in turn oscillates an arm carrying a spring-pressed pawl arranged to engage with and actuate a ratchet-wheel, which latter imparts a corresponding movement to the mechanism and trough for intermittently feeding and pressing the strip or ribbon of tobacco prior to being severed into filler-sections by the initial cutter or knife. The angular movement of said pawl is constant and uniform and is arranged to rotate the ratchet-wheel in one direction only. A curved guard member is interposed between the pawl and the periphery of the wheel. The said guard is secured to or integral with an index finger or pointer, which latter registers with a suitably-graduated stationary dial or plate provided with a series of holes to receive a pin mounted in the outer end of the pointer. These graduations correspond with and indicate the length of the filler sections or bunches to be produced.

By means of the above arrangement it will be apparent that the position of the pointer determines the length of the section to be severed from the ribbon of tobacco, and since the guard bears a fixed relation to the pointer it follows that as the guard is advanced in the direction of rotation of the ratchet-wheel and secured in position the length of the "feed" will be correspondingly lessened. This result is due to the fact that the interposed guard serves to keep the vibrating pawl idle or disengaged from the ratchet-wheel during the greater portion of its (the pawl's) move-

ment. By setting the guard in the opposite direction the length of the sections will be proportionately increased. It may be added that the movement of the vibrating pawl 5 itself (which is invariable) actuates the wheel, the net angular movement of the latter being that of the pawl or pawl-arm minus the angular distance that it rides upon the guard.

Another part of my present invention relates 10 in providing a cigar-bunching machine with means for automatically stopping the tobacco-feeding device whenever the quantity of fillers in the magazine exceeds a fixed or predetermined amount. In this device a 15 loosely-mounted horizontally-arranged gage-rod is employed having two collars adjustably secured thereon and parallel with the stem or rod of the plunger, which transfers the filler-sections singly into the magazine. In this 20 arrangement the gage-rod is adapted to be advanced by the action of the plunger, so that the inner end portion of the rod will lie in the path of the pawl before referred to.

Means are employed for positively disengaging the pawl from the wheel's teeth at each reciprocation of said rack and gear, the gage-rod serving to tilt the pawl downwardly into reengagement with the wheel upon the return stroke, or, in other words, the feeding 30 mechanism is rendered normally inoperative during one-half of each oscillation of the gear and pawl carrying arm, and is normally operative during the other half of the movement. In case, however, the magazine contains 35 an excess quantity of the fillers the inner end of the previously-adjusted gage-rod will not extend to the pawl. Consequently the latter will not be tripped until more of the fillers in the magazine have been converted 40 into bunches. Whenever the rod again advances to or past the ratchet-wheel, the positive action of the pawl-carrying arm will swing the heel of the pawl against the rod, thereby tripping the pawl, which in turn 45 engages the wheel's teeth and restarts the feeding mechanism, all as will be more fully hereinafter set forth and claimed.

In the accompanying four sheets of drawings, Figure 1 is a partial plan view of a cigar-bunching machine embodying my improvements. Fig. 2 is a side elevation, in partial section, enlarged scale, taken substantially on line 1 1 of Fig. 1. Fig. 3 is a transverse section taken on line 2 2 of Fig. 2. Fig. 4 is a similar sectional view, being practically a continuation of Fig. 3, and showing the traveling trough. Fig. 4½ is an end view of the pawl-guard and index-finger represented in Fig. 3. Fig. 5 is a longitudinal sectional view, in reduced scale, taken substantially on line 5 5 of Fig. 1, showing the plunger and its carriage retracted, corresponding with the normal position. Fig. 6 is a similar sectional view showing the plunger, &c., advanced and 60 forcing the filler-sections ahead in the magazine. Fig. 7 is a side elevation, in partial section, showing a portion of the feeding de-

vice sectionally represented in Fig. 3. Fig. 8 is a corresponding end view showing the pawl in the act of being automatically released from the wheel and being substantially at the end of the forward movement. Fig. 9 shows the pawl released, the arm at the same time carrying it rearwardly to re-engage the ratchet-wheel. Fig. 10 shows the 75 pawl in the act of being tripped by the gage-rod preparatory to rotating the wheel, &c., upon the return stroke. Fig. 11 shows the relation of the pawl, &c., at the commencement of the return movement, the position 80 of the guard corresponding, say, with the maximum feed; and Fig. 12 is a similar view showing the guard advanced so as to rotate the wheel a less distance, thereby producing correspondingly shorter filler-sections. 85

I would state briefly and in a general way that in a cigar-bunching machine embodying my improvements (see Fig. 1) the leaves of tobacco are fed into a traveling trough B, which in turn carries them in the form of a 90 continuous strip or ribbon below a suitable ironing or pressing device C and from the latter to a vertically-reciprocating holder a', carrying an initial knife K, which severs the strip into sections t', termed "filler-sections." 95 The latter are then transferred singly into a contiguous magazine m, in which a yieldingly-mounted plunger E is adapted to force the fillers into a charging-pocket having a capacity for one bunch or charge, which latter is subsequently covered with a binder and converted into a rolled bunch in any suitable manner.

My present invention does not cover an organized cigar-bunching machine in its entirety 105 and adapted to perform the steps above recited, but rather to improved means for actuating and automatically controlling the feeding mechanism, so that the magazine may not be surcharged with the filler-sections, and 110 means for regulating the length of said sections, and consequently the bunches.

The following is a more detailed description of my improved feeding device and the manner of its operation. The continuously- 115 revolving driving-shaft u, Fig. 2, rotates the cam-shaft u² by means of a gear (not shown) meshing into a gear h, secured to shaft u², on which latter is also secured the barrel-cam D. A slideable rack r is mounted just above said cam, the same carrying a roll r' in continuous engagement with the cam's groove, the shape of the latter being such that the corresponding movements of the rack are suitably timed with respect to the cutting-off mechanism and the other coacting devices. A gear r² engages the teeth of the rack, the proportion, &c., of said members as drawn being such that each double reciprocation of the rack imparts an angular movement to said gear of about one hundred and eighty degrees in each direction and corresponding, say, to the maximum distance that the strip t of tobacco can be advanced at each "feed ac-

tion." To one end of the upper belt-driving shaft d^6 is secured a sprocket-wheel d^3 , which carries an endless chain d , passing over a suitably-mounted similar wheel d^4 , in turn driving suitable pulleys supporting the belts c , &c., to form the traveling trough for the strip of superposed leaves of tobacco, substantially as shown and described in said Patent No. 528,903 and to which latter mechanism I make no claim. Fig. 2 herewith shows a partial side view of the chain, &c., a portion being broken away, so as to more clearly represent the traveling trough which feeds the tobacco to the initial cutting-knife K, the latter in turn severing the strip into filler-sections t' , which are transferred singly into the magazine m . This severing device constitutes no part of the present application.

By referring to the sectional view Fig. 4 it will be seen that the upper and lower belts c (mounted on pulleys $c' c'$, secured to upper and lower oppositely-revolving shafts $d^6 d^7$, respectively) form between them a traveling trough or channel c^2 for the strip t of tobacco. The movements of said shafts and belts are intermittent and controlled by the cam D, &c. To the said shafts $d^6 d^7$ are secured intermeshing spur-gears $d^1 d^2$, respectively, the latter gear having a ratchet-wheel f secured thereto. (See Fig. 3.) In alinement with but independently of the shaft d^7 is located an arm or lever v , having a hub v' , to which is fastened the said rack-actuated gear r^2 . The upper end of the arm carries a swinging pawl y , adapted to engage the teeth of the wheel f and rotate it in the proper direction. Thus it will be seen that the belts c are actuated by the cam D, the said intermediate gearing, &c. Obviously the action of the rack, gear r^2 , lever v , and its pawl rotates the ratchet-wheel intermittently and in one direction only. Therefore if there were no intervening device the length of the sections severed by the initial cutting-knife K would be invariable.

In order to vary the feed or length of the filler-sections, so as to produce bunches having any desired length, I provide the device A, the same consisting of an arm or finger s and a guard-plate i' , united by the small central shaft or rod s' , Fig. 3. The guard is interposed between the pawl y and the periphery of the ratchet-wheel f in such manner that the pawl rides idly upon the guard, while at the same time the movement of the said rack and its gear are invariable. In the said device A for controlling the length of the filler-sections (and therefore the bunches) the finger s , secured to the outer end of the rod s' , carries at its upper end a spring-pin s^2 , registering with a series of holes p^2 , formed in a dial or index plate p' , secured to an extension p of the gear frame or housing. The dial, which as drawn has the form of a quadrant, Fig. 2, has near its outer edge a series of radial graduations indicating the corresponding length of sections adapted to be pro-

duced by the machine. The finger s has a pointer s^3 registering with the said graduations. The inner end of rod s' has as drawn a head $s^4 s^5$, to which is secured a flat plate i , having a bent guard i' , extending across and partly around the face of the ratchet-wheel f , as clearly shown in Figs. 3, 4 $\frac{1}{2}$, 7, 8, &c.

The point y' of the swinging pawl y is kept normally disengaged from the teeth of the wheel f by means of a spring y^2 , pressing against a pin y^3 , secured to the pawl. To the front end of the pawl-pivot pin y^6 , extending through the eye of the lever v , is secured a latch member y^5 , having a notch y^4 therein. The latch has an abutment or extension to support the end of a flat spring z when the latter is detached from said notch. This spring is secured to the lever v and is bent rearwardly at a point near the rim of the wheel f . When the spring is in the notch, the pawl is in normal slightly-yielding engagement with the ratchet-wheel or bearing against the guard i' . (See Figs. 10, 12, &c.)

It is to be borne in mind that the angular movement forth and back of the lever and its pawl is invariable or about one hundred and eighty degrees, as before stated. Contiguous to the wheel's rim and at a point near the end of the forward stroke of the pawl is located a small stationary pin or stop j , (see also Fig. 7,) arranged to contact with the moving spring z , and thus automatically withdraw it from the notch y^4 of the latch at substantially the same instant that the pawl ceases its forward movement, thereby permitting the spring y^2 to swing the pawl out of gear. Fig. 8 shows the spring in the act of being withdrawn, while Fig. 9 shows the same fully released, the pawl being on its return stroke and disengaged from the wheel, the latter meanwhile remaining stationary. The heel of the tilted pawl is slightly elevated, so that as it passes beneath a normally stationary gage-rod n , lying in its path, it engages the latter and is forced downwardly into engagement with the wheel f , thereby, too, at the same time correspondingly elevating the latch y^5 and permitting the spring z to enter the notch y^4 . Fig. 10 shows the corresponding relation of the parts. The continued movement rearwardly of the gear r^2 carries the lever v and pawl to its limit or substantially as shown in Figs. 11 and 12, wherein the parts are represented as having just started on the return forward stroke. In Fig. 11 the guard i' is set so as to produce the longer feed or angular movement of the wheel f and Fig. 12 a considerably shorter movement.

It is obvious that the foregoing action takes place at each double reciprocation or oscillation of the lever, &c., thereby intermittently actuating the trough, its ribbon of tobacco, &c., a corresponding extent. The degree of such movement is of course dependent upon the position of the finger s and connected guard i' . In case, however, there should be an excess quantity of filler-sections contained

in the magazine m the gage-rod n will not advance endwise sufficiently to engage the pawl. Therefore the latter will not be tripped, and as a result the feeding device will remain 5 temporarily inoperative until the continued action of the other parts of the machine shall have reduced the filler-sections in the magazine to the predetermined or desired amount.

The following is a more detailed description of the mechanism which controls the action of the gage-rod: In the said Gardner patent, No. 528,903, means are employed for pressing the filler-sections into a magazine through the medium of a weighted or yieldingly-mounted plunger and carriage. Therefore I make no claim herewith to such a device; but in order to properly show the relation of such old devices to my present improvements I have deemed it best in Figs. 1, 15 and 6 to illustrate portions of said machine. To the under side of the bed or frame e' is slidably mounted a carriage a , having a longitudinally-extending rack in engagement with and actuated by a segment-gear a^3 , in 20 turn operated by a suitably-connected cam L , secured to the driving-shaft u . The carriage has an arm extending upwardly through an opening e^2 , formed in the frame, carrying a wheel a^2 , from which a cord passes over 25 a winding drum or wheel w' , the other end of the cord being fast to the rear end of the plunger-rod e . The wheel w' is mounted on an axle carrying a smaller wheel provided with a cord w^2 and weight w . The plunger-rod e extends centrally and longitudinally of 30 the machine and passes loosely through the said arm of the carriage. The forward end of the rod has a plunger E , adapted to press the filler-sections t' from the transferring-chamber c^6 into the magazine m . The reciprocating movements of the carriage and its wheel a^2 are positive and invariable and are effected by a suitable cam L . The forward 35 movement of the plunger is, however, variable, the distance traveled being as a rule much less than the corresponding travel of the carriage. This variation is due to the amount of fillers in the magazine and also to the degree of pressure exerted by the weight 40 w in propelling the plunger ahead, it being understood that it is the pressure of the weight alone that advances and compresses the fillers in the magazine. The plunger-rod e passes loosely through the said wheel-carrying arm 45 and has a collar a^4 , adjustably secured thereon, bearing normally against the rear face of the arm. At substantially the same instant that the plunger engages the filler-sections the continued forward movement of the carriage causes the latter to withdraw from the collar, thereby permitting the weight to fall and freely exert its force upon the plunger. On the return or rearward stroke of the carriage the latter upon engaging the collar a^4 50 operates to retract the rod e and its plunger until the end of the stroke is reached, the parts then being in the normal position, sub-

stantially as represented in Fig. 5, the weight w meanwhile being correspondingly elevated.

The action of the gage-rod n is dependent upon the movements of the plunger-rod, although not necessarily operative at each stroke—that is to say, the gage-rod, as drawn, lies parallel with, to the right, and somewhat above the plunger-rod. It is mounted to move freely in suitable supports and carries front and rear dogs or collars n^2 n' , respectively, adjustably secured thereon. The inner end of the rod n is arranged to travel past the face of the ratchet-wheel f (see dotted lines, Fig. 5) and is adapted to be actuated back and forth endwise by means of an arm e^3 , secured to the plunger-rod. In case the adjustment and conditions are such that the arm e^3 in its forward movement engages the front dog n^2 the gage-rod will be correspondingly advanced, and thus render the feeding device operative. The return or rearward movement of the plunger causes the arm to positively engage the rear dog n' and retract the gage-rod to its normal position. While the member n remains in this latter position the feeding device will continue to be inoperative, because it then cannot trip the pawl y , as hereinbefore stated.

I would add that the strip of uncut fillers t may sometimes slightly exceed the normal width, or the charging-pocket into which the fillers are pressed from the magazine to form the bunch may be adjusted to a narrower width. In such event it follows that the relative action of the feeding device to the plunger would be considerably in excess of the latter. In practice I prefer to set the collar n^2 so that the feeding mechanism will be operative when the plunger advances, say, somewhat beyond the point X . (See dotted lines, Fig. 5.) When the filler-sections accumulate in the magazine to said point X , (see Fig. 6,) the gage-rod will remain inoperative for the time being, (and consequently the ratchet-wheel,) since the movement of the rod e would be insufficient to cause the arm e^3 to engage the collar n^2 . The next two or three revolutions of the machine would, however, permit the plunger to gradually advance sufficiently to again set the feeding device into action.

I may state here that usually each filler-section t' contains tobacco sufficient for a number of bunches. Consequently the feeding mechanism is or may be inoperative correspondingly. In lieu of adapting the feeding means to work at each revolution of the machine or reciprocation of the plunger, except as modified by the excess quantity of fillers in the magazine, as hereinbefore stated, it may be readily arranged to become operative at a relatively slower rate without reducing the plunger's speed and at the same time retaining the device for stopping the feed action in case of the accumulation of fillers in the magazine in excess of the normal or predetermined amount.

I claim as my invention—

1. In a cigar-bunching machine, the combination with a tobacco-feeding mechanism, a magazine communicating therewith, and a plunger arranged to advance the tobacco in the magazine, of means for causing the plunger mechanism to vary the action of the feeding mechanism.
2. In a cigar-bunching machine, the combination with a tobacco-feeding mechanism, a magazine communicating therewith, and a plunger arranged to advance the tobacco in the magazine, of means for causing the plunger mechanism to retard the normal action of the feeding mechanism when the tobacco in the magazine exceeds a predetermined quantity.
3. In a cigar-bunching machine, the combination with a tobacco-feeding mechanism, a magazine communicating therewith, and a plunger arranged to advance the tobacco in the magazine, of means for causing the plunger mechanism to render the feeding mechanism temporarily inoperative when the tobacco in the magazine exceeds a predetermined quantity.
4. In a cigar-bunching machine, the combination with a tobacco-feeding mechanism, a magazine communicating therewith, and a plunger arranged to advance the tobacco in the magazine, of means for causing the plunger mechanism to retard the normal action of the feeding mechanism when the tobacco in the magazine exceeds a predetermined quantity, and means for adjusting said latter means to vary said predetermined quantity.
5. In a cigar-bunching machine, the combination with an intermittently-movable tobacco-feeding mechanism, a magazine communicating therewith, and a plunger arranged to advance the tobacco in the magazine, of means connected with the plunger mechanism for causing the feeding mechanism to omit one or more steps in its intermittent movement when the tobacco in the magazine exceeds a predetermined quantity.
6. In a cigar-bunching machine, the combination with a feeding device provided with a ratchet-wheel through which power is transmitted to actuate the device, an oscillating pawl having an invariable angular movement and arranged to engage said wheel, and a gage-rod arranged to lie normally in the path of and to engage with and strip said pawl, a magazine, a plunger arranged to press the tobacco ahead in the magazine, the plunger being arranged to move the gage-rod out of position of engagement with said pawl when the quantity of tobacco in the magazine extends to a predetermined point.
7. In a cigar-bunching machine, the combination with a feeding device provided with a ratchet-wheel through which power is transmitted to actuate the device, an oscillating pawl having an invariable angular movement and arranged to engage said wheel, and a gage-rod arranged to lie normally in the path of and to engage with and strip said pawl, a magazine, a plunger arranged to press the tobacco ahead in the magazine, means for causing the plunger to engage with and thereby advance and retract the gage-rod at its forward and rearward positions respectively, and means for adjusting the said positions of engagement.
8. In a cigar-bunching machine, the combination of a tobacco-feeding device, a ratchet-wheel through which the device is adapted to be rotated in one direction only, an oscillating pawl moving an invariable angular distance back and forth at each revolution of the machine, a magazine, a plunger arranged to press the tobacco in the magazine, means for moving the plunger, a rod having the plunger secured to its front end and carrying an arm, an endwise-movable gage-rod passing loosely through the said arm, a collar secured to the rod on each side of said arm, the collar being arranged whereby the plunger in its forward movement causes said arm to engage one of the collars and advance the gage-rod into a position to engage with and move the said pawl downwardly onto the wheel and thus rotate the latter on the return movement of the pawl and thereby actuate the feeding device, the other collar being so arranged that on the rearward movement of the plunger said arm will engage this collar and thereby return the gage-rod to its normal or non-operative position.
9. In a cigar-bunching machine, a tobacco-feeding device provided with a ratchet-wheel through which the device is operated, an oscillating arm carrying a spring, a spring-pressed pawl mounted in the outer end of said arm and arranged to engage the teeth of and rotate the wheel, a notched latch connected with and moving in unison with the pawl and arranged to receive the free end of said spring at its notch, a fixed stop arranged to engage with and detach the spring from the notched portion of said latch just before said arm and attached parts complete the forward stroke, thereby permitting the pawl to swing upwardly out of engagement with the wheel, and an automatically-actuated gage-rod located in the path of the pawl, and so arranged that the pawl in its rearward movement strikes the rod and is moved downward into engagement with the ratchet-wheel whereby said spring is permitted to enter the notched part of the latch.

Signed at Providence, Rhode Island, this 3d day of August, 1901.

MICHAEL M. GARDNER.
